UNITED STATES PATENT OFFICE.

ELEAZER C. BENNETT, OF EAST BRIDGEWATER, MASSACHUSETTS.

METHOD OF UNITING THE SOLES AND UPERS OF BOOTS OR SHOES.

SPECIFICATION forming part of Letters Patent No. 336,548, dated February 23, 1886.

Application filed August 19, 1885. Serial No. 174,840. (No model.)

To all whom it may concern:

Be it known that I, ELEAZER C. BENNETT, of East Bridgewater, in the county of Plymouth and State of Massachusetts, have invented certain new and useful Improvements in the Method of Making Boots and Shoes, of which the following, taken in connection with the accompanying drawings, is a specification.

My invention has for its object the fastening of the bottom of boots or shoes to the vamps by means of a compound peg, said peg being made and inserted by a series of operations. Said series of operations, embodying my invention, are illustrated by the following drawings, in which—

Figure 1 is a section of the soles and vamps of a shoe, showing a puncture as made by an awl and ready to receive the peg. Fig. 2 is a section of the soles and vamps, showing the metal part of the peg inserted. Fig. 3 is a section of the soles and vamps, showing the outer part of the peg having its lower end headed. Fig. 4 is a section of the soles and vamps, showing the outer part inserted and headed and the core in place as left by the hammer; and Fig. 5 is a section of the soles and vamps, showing the completed peg.

In order to manufacture boots and shoes cheaply and rapidly, I have devised a machine, which is fully set forth in the drawings and specifications accompanying my application of even date for Letters Patent on a machine for making compound pegs, and for using the same in the manufacture of boots and shoes.

In the drawings, A represents the outer sole; B, the inner sole, and C the vamp.

The first step in my method consists in the process of lasting, which may be done in the usual manner; second, the last is withdrawn

and the boot and shoe placed upon some suitable support, so that the puncture D, Figs. 1 and 2, may be made; third, the puncture D being made, which is perfectly rectangular in section, a doubled wire, H H' H'', Fig. 2, is inserted; fourth, the doubled wire is headed, as shown at H', Figs. 3, 4, and 5; fifth, the core P is driven in, as shown in Figs. 4 and 5; and, lastly, the top of the peg is cut off level with the sole. This completes the fastening of the boot or shoe.

From the above it may be seen that my fastening is composed of two parts, and the advantage gained is, that one part has a head, which will prevent the peg from working out, while the other part—that is, the core—is made of wood or metal. Thus each part is made to draw against the other part. This arrangement constitutes a fastening for holding together the several layers of leather of which a shoe-bottom is composed, so that they cannot be separated in wearing.

I claim—

That improvement in uniting the upper and soles of boots and shoes which consists in placing the lasted boot or shoe upon a suitable support, perforating the parts, then inserting a two-part metallic fastening, driving or forcing a core within such fastening, and then cutting off the projecting portions, all substantially as set forth.

In testimony whereof I have signed my name to this specification, in the presence of two subscribing witnesses, on this 8th day of June, A. D. 1885.

ELEAZER C. BENNETT.
